To all whom it may concern:

Be it known that I, ALEXANDER KOHUT, a citizen of the United States, residing at 27 West 96 Street, New York, New York, have invented a new, original, and ornamental Design for a Textile Fabric or Similar Article, of which the following is a specification, reference being had to the accompanying drawing, forming a part thereof.

The figure is a plan view of a textile fabric
showing my new design.

I claim:

The ornamental design for a textile fabric or similar article as shown.

In testimony whereof I have signed this specification.

ALEXANDER KOHUT.
